RAILWAY SIGNAL-LAMP CONTROLLER.

1,174,935.

Specification of Letters Patent.

Patented Mar. 7, 1916.

Application filed July 10, 1915. Serial No. 39,180.

To all whom it may concern:

Be it known that I, WINTHROP K. HOWE, a citizen of the United States, and a resident of the city of Rochester, in the county of Monroe and State of New York, have invented a new and useful Railway Signal-Lamp Controller, of which the following is a specification.

This invention relates to a device for use in each railway track block or in adjoining blocks for controlling electric signal lamps governing the movements of railway trains from one block into another.

The invention has for its main object to provide a simple, inexpensive and durable signal lamp controller capable of automatically lighting the "clear" and "danger" signal lamps and later automatically dimming them to obviate too dazzling effect upon the engineer or motorman as the train or car approaches the lamps, which are automatically extinguished by passage of the train or car from the block, and whereby electric energy is saved by consuming current only when the lamps are needed for signaling purposes, and thereby also prolonging the life of the signal lamps.

Other objects and advantages will appear as the description of the invention progresses, and the novel features of the invention will be particularly pointed out in the appended claims.

Reference is made to the accompanying diagrammatic drawing, forming part of this specification, and which indicates two of the improved controllers in operative relation with "clear" and "danger" signal lamps at railway track block sections.

The numerals 1, 2, indicate the rails of a railway track which have insulating joints at 3, dividing the track into block sections of which the diagram shows a short part of block 4, the whole of blocks 5, and 6, and a still shorter portion of block 7. The main line wires 8, 9, are connected to an alternating current generator 10, supplying electric energy for lighting the signal lamps and for operating reactance devices which are influenced by the track circuits in manner hereinafter explained. From the respective wires 8, 9, wires 11, 12, and 13, 14, lead to the primary coils 15, 16, of two respective step-down transformers 17, 18, having secondary coils 19, 20, inductively taking cur-

rent from the primary coils in well known manner.

One of similar track block circuits now will be described by starting at the positive pole of the centrally shown secondary coil 19, thence by wire 21, to the rail 1, of block 5, and by wire 22, to and through the coils of an alternating current track relay 23, and by wire 24, to track rail 2, thence by wire 25, to a coil 26, surrounding the iron core 27, of an electromagnetic impedance device 28, shown at the right-hand in the diagram, and from said coil 26, by wire 29, to the negative pole of secondary coil 19. The partial circuit from the secondary coil 19, of the extreme left-hand transformer 17, to the track rails 1, 2, of block 4, and through the coil 26, of the left-hand reactance device by wires 21, 25, 29, is shown in the diagram, but the track relay for said cut-away block 4, is omitted to accommodate illustration 75 which also compels omission of the reactance device coacting with the rails of track block 6, the relay 23, and rail wire connections 22, 24, for which are shown.

The relay 23, of each track block attracts 80 an armature 30, adapted to respective upper and lower fixed contacts 31, 32, in circuit with which are certain hereinafter named wires leading from the secondary coils 20, of transformers 18, to the reactance devices 85 28, and to two respective green and red "clear" and "danger" light signals marked G and R, and erected at or near the entrance to each track block, the light signals for blocks 5, and 6, being shown in the diagram. 90 Similar circuits through the secondary coils 20, of transformers 18, to the light signals and reactance device 28, of each track block may be traced as follows, it being remembered that the constant energizing of the 95 track block circuits by the transformers 17, normally energizes the track relays 23, when no train or car is in the block, thereby attracting the relay armature 30, and closing a circuit from the positive pole of secondary 100 coil 20, by wire 33, to armature 30, contact 31, and wire 34, to one terminal of the "clear" lamp G, and from its other terminal to wire 35, and junction point 36, and thence by a common wire 37, to a relatively fixed 105 resilient contact 38, and thence to a switch arm 39, fixed to a Z shaped armature 40, of the reactance device 28, when said armature

40, by turning under magnetic influence of the poles of the energized reactance core 27, moves its arm 39, to the contact 38, thereby completing the green lamp circuit from 5 switch arm 39, by wire 41, to a coil 42, surrounding the core 27, of reactance 28, and thence by wire 43, to the negative pole of secondary coil 20. Because of its far less resistance than that of the track relay 23, 10 a train or car entering track block 5, or 6, immediately short circuits or shunts and thus deenergizes relay 23, thereby permitting its armature to drop away from its front contact 31, and engage its back contact 32, thus closing the circuit from secondary coil 20, through the "danger" lamp R, by way of wire 33, armature 30, contact 32, wire 44, to one terminal of lamp R, the other terminal of which is connected by 15 a wire 45, to junction point 36, and thence as in the aforesaid "clear" lamp circuit through wire 37, contact 38, switch arm 39, wire 41, reactance coil 42, and wire 43, to the negative terminal of coil 20. A weight 46, 20 is shown applied to the arm 39, of armature 40, for retarding the counterclockwise turning of the armature under influence of the energized reactance core 27, and to automatically return said armature to the illustrated 25 normal position, and an auxiliary weight 47, may be hung by a flexible cord 48 to offer additional retarding resistance to turning of the armature during the latter part of its movement, all as may be determined by the form and arrangement of the light circuit transformer 18, and reactance coil 42, relatively to the track circuit transformer 17 and the coil 26, on the reactance core 27.

30 Let it be assumed that a train or car is running along track block 4, in direction of the arrow a, and that no train or car is in the following block 5. Under these conditions the left-hand green or "clear" signal lamp G, at the junction of blocks 4, and 5, would be lit automatically because of engagement of contacts 39, 38, of the left-hand reactance 28, almost immediately its armature 40 began to turn counterclockwise 35 under influence of the electro-magnetic circuit established through the coil 19, of the first shown transformer 17, the left-hand reactance coil 26, and its energized core 27. As the train or car first entered block 4, the 40 resistance offered by its track rails 1, 2, was at its highest due to inclusion in the track circuit of all those longer portions of the rails of block 4, in advance of the train or car, and consequently the track circuit reactance coil 26, would have the least magnetizing effect on the reactance core 27, but still ample to cause turning of the reactance armature 40, counterclockwise far enough 45 to engage the reactance armature arm 39, with the contact 38, and close the lamp cir-

cuit through the coil 20, of the first transformer 18, to automatically light the green "clear" lamp G, and thus notify the motorman of the train or car advancing in block 4, that there is no train or car in the following block 5, which thus may safely be entered. After the above traced green lamp circuit is closed to light the lamp G, as aforesaid at the forward end of block 4, the reactance coil 42, in said circuit has a magnetizing effect on the reactance core 27, auxiliary to that of the track circuit coil 26, thereby assisting the reactance track circuit coil 26, in drawing the reactance armature 40, around further counterclockwise to 70 cut more lines of force of the electromagnetic circuit through the reactance armature and core and consequently increase the counter-electromotive force, thereby increasing the resistance in the green lamp circuit 75 and automatically but gradually dimming the light of the green lamp G to avoid too dazzling effect of it upon the eyes of the motorman of the train or car advancing in the block 4. This gradual light-dimming 80 effect depends less upon the above named auxiliary magnetizing effect of the lamp circuit reactance coil 42, on the reactance core 28, than it does upon the gradual decrease of the length of the rails of block 4, in 85 front of the advancing train or car as this decreasing rail length lessens the resistance of the block rails and therefore proportionately increases the magnetizing effect of the above traced track circuit through the transformer coil 19, and the reactance coil 26, upon the reactance armature 40, to assure 90 its full counterclockwise movement across maximum number of lines of force at the reactance core 27, to thereby increase the resistance in the lamp circuit for dimming the light as aforesaid. The weights 46, 47, on and above the reactance armature 40, promote slow counterclockwise turning of this armature for gradually dimming the light 95 as the train or car advances along track block 4, but any other approved means mechanically or electrically retarding this armature movement may be employed.

If while a train or car is advancing on 100 block 4, another car should be in the preceding block 5, said other car would shunt and deenergize the left-hand relay 23, and its armature 30, would drop to the back contact 32, thereby closing the above 105 traced "danger" lamp circuit through the coil 20, of the first transformer 18, and automatically lighting the red lamp R, to thus advise the motorman of the train advancing on block 4, that the preceding block 110 5, is occupied and may not safely be entered until after the red lamp is automatically extinguished by passage of said preceding train from block 5, into block 6, or beyond it. As the train or car leaves block 4, and 115

enters block 5, from which the preceding train had passed, the green light would automatically be extinguished and the red light would automatically be lighted to warn the motorman of the next following train advancing in block 4, that block 5, may not safely be entered. Should the red lamp R, be lighted by reason of the presence of a train or car in block 5, and as a warning to the motorman of a car advancing in block 4, the red light also would be automatically and gradually dimmed in manner similar to the dimming of the green lamp G, as above described.

The automatic lighting and dimming and extinguishment of the right-hand green and red lamps G¹ and R¹, at the junction of track blocks 5, and 6, is similar to that above described relatively to like lamps G and R, located at the junction of blocks 4, and 5, and needs no further detailed description, but it may be briefly stated that should block 6, be clear and a train be approaching block 5, the right-hand green lamp G¹ would be lighted by closing of its circuit through the second or right-hand transformer coil 20, and the coil 42, of the right-hand resistance 28, after its contacts 39, 38, had been engaged by initial counter-clockwise turning of its armature 40, by energization of the reactance coil 26, and core 27, through the track circuit of block 5, and the centrally shown transformer coil 19; and as the train or car advances in block 5, thereby shortening the length of the block rails in front of it, the operation of the right-hand reactance 28, will automatically cause dimming of the lighted green lamp G¹, as the car approaches the end of block 5, and this lamp will be extinguished automatically as the car leaves block 5, and enters block 6. Should a train or car be in block 6, while a train is advancing in block 5, the right-hand track relay 23 would be deenergized thereby causing closing of the circuit of the second red lamp R¹, through the right hand transformer coil 20, and coil 42 of the right-hand reactance 28, thereby lighting the red lamp to warn the motorman of said following train, and when the train or car leaves block 6, the red lamp will automatically be extinguished. The secondary coil 19, of the extreme right-hand transformer 17, is in circuit with the not shown reactance in block 7, and which coacts with the track circuits of block sections 6, and 7, in manner readily understood from the aforesaid description. The passage of a train or car from a block section extinguishes the green or red light because such passage deenergizes the coil 26, of the reactance 28, and thus permits the armature 40, with its arm 39, to gravitally return to the illustrated normal position and separate the contacts

39, 38, thereby breaking the lamp lighting circuit.

Although I have particularly described the construction of one physical embodiment of my invention, and explained the operation and principle thereof; nevertheless, I desire to have it understood that the form selected is merely illustrative, but does not exhaust the possible physical embodiments of the idea of means underlying my invention.

What I claim as new and desire to secure by Letters Patent of the United States, is:

1. A signal lamp controller for block system railways including track sections and an electric circuit traversing each track section; a signal lamp at the forward end of each track section approached by a car traveling on said section, a lamp circuit including means lighting said lamp, and means influenced by the track circuit and dimming the lamp as the car approaches the forward end of the track section.

2. A signal lamp controller for block system railways including track sections and an electric circuit traversing each track section; a signal lamp at the forward end of each track section approached by a car traveling on said section, a lamp circuit including means lighting said lamp, and a reactance device influenced by the track circuit and dimming the lamp as the car approaches the forward end of the track section.

3. A signal lamp controller for block system railways including track sections and an electric circuit traversing each track section; a signal lamp at the forward end of each track section approached by a car traveling on said section, a lamp circuit including means lighting said lamp, and a reactance device included in both track and lamp circuits and dimming the lamp as the car approaches the forward end of the track section.

4. A signal lamp controller for block system railways including track sections and an electric circuit traversing each track section; a source of electric energy for each track section circuit, a signal lamp at the forward end of each track section approached by a car traveling on said section, a second source of electric energy, a lamp circuit including means lighting the lamp from said second energy source, and means included in both track and lamp circuits and dimming the lamp as the car approaches the forward end of the track section.

5. A signal lamp controller for block system railways including track sections and an electric circuit traversing each track section; a source of electric energy for each track section circuit, a signal lamp at the forward end of each track section ap-

- proached by a car traveling on said section, a second source of electric energy, a lamp circuit including means lighting the lamp from said second energy source, and a reactance device included in both track and lamp circuits and dimming the lamp as the car approaches the forward end of the track section.
6. A signal lamp controller for block system railways including track sections and an electric circuit traversing each track section; a signal lamp at the forward end of each track section approached by a car traveling on said section, a lamp circuit including means lighting said lamp, a reactance device responding to gradual cutting out of track rail resistance by an advancing car, and means retarding operation of the reactance device thereby gradually dimming the lamp as the car approaches the forward end of a track section.
7. A signal lamp controller for block system railways including track sections and an electric circuit traversing each track section; a signal lamp at the forward end of each track section approached by a car traveling on said section, a lamp circuit including means lighting said lamp, a reactance device responding to gradual cutting out of track rail resistance by an advancing car, and a weight retarding operation of the reactance device thereby gradually dimming the lamp as the car approaches the forward end of a track section.
8. A signal lamp controller for block system railways including track sections and an electric circuit traversing each track section; a source of electric energy for each track section circuit, a signal lamp at the forward end of each track section approached by a car traveling on said section, a second source of electric energy, a lamp circuit including means lighting the lamp from said second energy source, a reactance device included in both track and lamp circuits and responding to gradual cutting out of track rail resistance by an advancing car, and means retarding operation of the reactance device thereby gradually dimming the lamp as the car approaches the forward end of a track section.
9. A signal lamp controller for block system railways, comprising a track circuit, a signal lamp, a lamp circuit, a reactance device included in both track and lamp circuits and dimming the lamp as a car approaches the end of a track section, and means retarding operation of the reactance device.
10. A signal lamp controller for block system railways, comprising a block circuit, a signal lamp, a lamp circuit, a reactance device included in both track and lamp circuits and dimming the lamp as a car approaches the end of a track section, and a

weight retarding operation of the reactance device.

11. A signal lamp controller for block system railways, comprising a track circuit including a source of electric energy; a signal lamp, a lamp circuit including an independent energy source, a reactance device included in both track and lamp circuits and dimming the lamp as a car approaches the end of a track section, and means retarding operation of the reactance device.

12. A signal lamp controller for block system railways, comprising a track circuit for each block section including a source of electric energy, the track rails, and a relay, "clear" and "danger" signal lamps for each block, and two respective lamp circuits which include respective front and back contacts of the relay armature, and means included in the track and lamp circuits and dimming either the "clear" or "danger" lamp as a car approaches the end of a block section.

13. A signal lamp controller for block system railways, comprising a track circuit for each block section including a source of electric energy, the track rails, and a relay; "clear" and "danger" signal lamps for each block, and two respective lamp circuits which include respective front and back contacts of the relay armature, and a reactance device included in the track and lamp circuits and dimming either the "clear" or "danger" lamp as a car approaches the end of a block section.

14. A signal lamp controller for block system railways, comprising a track circuit for each block section including a source of electric energy, the track rails, and a relay; "clear" and "danger" signal lamps for each block, and two respective lamp circuits which include an independent energy source and the respective front and back contacts of the relay armature; and means included in the track and lamp circuits and dimming either the "clear" or "danger" lamp as a car approaches the end of a block section.

15. A signal lamp controller for block system railways, comprising a track circuit for each block section including a source of electric energy, the track rails, and a relay; "clear" and "danger" signal lamps for each block, and two respective lamp circuits which include an independent energy source, and the respective front and back contacts of the relay armature; and a reactance device included in the track and lamp circuits and dimming either the "clear" or "danger" lamp as a car approaches the end of a block section.

16. A signal lamp controller for block system railways, comprising a track circuit for each block section including a source of electric energy, the track rails, and a relay; "clear" and "danger" signal lamps for

each block, two respective lamp circuits which include respective front and back contacts of the relay armature, and a reactance device included in the track and lamp circuits and dimming either the "clear" or "danger" lamp as a car approaches the end of a block section; said reactance device comprising a core, two energizing coils thereon, one coil in the track circuit and the other coil in both lamp circuits, an armature movable by the energized core, a relatively fixed contact, and a contact on the movable reactance armature which when the reactance core is energized engages the fixed contact thereby closing either lamp circuit and initiating lamp dimming operation of the reactance.

17. A signal lamp controller for block system railways, comprising a track circuit for each block section including a source of electric energy, the track rails, and a relay; "clear" and "danger" signal lamps for each block, and two respective lamp circuits which include respective front and back contacts of the relay armature, a reactance device included in the track and lamp circuits and dimming either the "clear" or "danger" lamp as a car approaches the end of a block section, and means retarding operation of the reactance device.

18. A signal lamp controller for block system railways, comprising a track circuit for each block section including a source of electric energy, the track rails, and a relay; "clear" and "danger" signal lamps for each block, and two respective lamp circuits which include an independent energy source and respective front and back contacts of the relay armature, a reactance device included in the track and lamp circuits and dimming either the "clear" or "danger" lamp as a car approaches the end of a block section, and means retarding operation of the reactance device.

19. A signal lamp controller for block system railways, comprising a track circuit for each block section including a source of electric energy, the track rails, and a relay; a "clear" signal lamp, a reactance device including a core, two energizing coils thereon, an armature carrying a contact and movable by the energized core; an electric circuit including said energy source and the rails of one block and one energizing coil on the reactance core; and another electric circuit including the "clear" lamp, an energy source, the attracted armature of the energized relay of the block ahead, a relatively fixed contact engaged by the moved reactance armature contact, and the other energizing coil on the reactance core and thence back to the lamp energy source, whereby when a car enters a track section and the block ahead is clear the "clear" signal lamp will be automatically lighted and will be dimmed by

the reactance as the car advances in the block and will be extinguished as the car leaves the block.

20. A signal lamp controller for block system railways, comprising a track circuit for each block section including a source of electric energy, the track rails, and a relay; a "danger" signal lamp, a reactance device including a core, two energizing coils thereon and an armature carrying a contact and movable by the energized core; an electric circuit including said energy source and the rails of one block and one energizing coil on the reactance core; and another electric circuit including the "danger" lamp, an energy source, the dropped armature of the deenergized relay of the block ahead, a relatively fixed contact engaged by the moved reactance armature contact and the other energizing coil or the reactance core and thence back to the lamp energy source, whereby when a car enters a track section and the block ahead is occupied, the "danger" signal lamp will be automatically lighted and will be dimmed by the reactance as the car advances in the block and will be extinguished as the car leaves the block.

21. A signal lamp controller for block system railways, comprising a track circuit for each block section including a source of electric energy, the track rails and a relay; "clear" and "danger" signal lamps for each block, a reactance device for each block including a core, two energizing coils thereon and an armature carrying a contact and movable by the energized core; an electric circuit including said energy source and the rails of one block and one energizing coil on the reactance core, two other electric circuits one for each lamp and having a common energy source, the "clear" lamp circuit including said common energy source and the attracted armature of the energized relay of the block ahead, a wire leading to said "clear" lamp and another wire leading from it to a junction point; and the "danger" lamp circuit including said common lamp energy source and the dropped armature of the same deenergized relay and a wire leading to the same junction point; and a continued common circuit for both lamps including a wire from said junction point to a relatively fixed contact engaged by the moved reactance armature contact and thence to the other energizing coil on the reactance core and back to the lamp energy source.

22. A signal lamp controller for block section railways, comprising a reactance device including a core, two energizing coils thereon, an armature carrying a contact and movable by the energized core, a source of electric energy, an electric circuit including said energy source and the rails of one block and one energizing coil on the reactance

core, a relay in circuit with the rails of the block ahead, a signal lamp, a lamp circuit including another energy source, the armature of the relay of the block ahead, a relatively fixed contact engaged by the moved reactance armature contact and the other energizing coil on the reactance core.

23. A signal lamp controller for block section railways, comprising a reactance device including a core, two energizing coils thereon, an armature carrying a contact and movable by the energized core, a source of electric energy, an electric circuit including said energy source and the rails of one block and one energizing coil on the reactance core, a relay in circuit with the rails of the block ahead, a signal lamp, a lamp circuit including another energy source, the armature of the relay of the block ahead, a relatively fixed contact engaged by the moved reactance armature contact and the other energizing coil on the reactance core; and means retarding movement of the reactance armature as a car approaches the end of a block section.

24. A signal lamp controller for block system railways, comprising a track circuit for each block section including a source of electric energy, the track rails and a relay;

"clear" and "danger" signal lamps for each block, a reactance device for each block including a core, two energizing coils thereon and an armature carrying a contact and movable by the energized core; an electric circuit including said energy source and the rails of one block and one energizing coil on the reactance core, two other electric circuits one for each lamp and having a common energy source, the "clear" lamp circuit including said common energy source and the attracted armature of the energized relay of the block ahead, a wire leading to said "clear" lamp and another wire leading from it to a junction point; and the "danger" lamp circuit including said common lamp energy source and the dropped armature of the same deenergized relay and a wire leading to the same junction point; and a continued common circuit for both lamps including a wire from said junction point to a relatively fixed contact engaged by the moved reactance armature contact and thence to the other energizing coil on the reactance core and back to the lamp energy source; and means retarding movement of the reactance armature as a car approaches the end of a block section.

WINTHROP K. HOWE.
